BOAT HULL OR SIMILAR ARTICLE

George A. Moore, Encinitas, Calif.

Application November 26, 1954, Serial No. 33,259

Term of patent 14 years

(Cl. D71—1)

Fig. 3

Fig. 2

Fig. 4

Figure 1 is a perspective view of a boat hull or similar article, showing my new design;

I claim:

The ornamental design for a boat hull or similar article, as shown.
